UNITED STATES PATENT OFFICE

ERNEST LOESSER AND ERNEST W. LOESSER, OF MALBA, NEW YORK, ASSIGNEES, BY
MESNE ASSIGNMENTS, TO NEW DIAMOND POLISHING TOOL COMPANY OF AMERICA,
INC.

DOP-CASTING APPARATUS

Application filed April 23, 1929. Serial No. 357,427.

This invention relates to a dop casting apparatus and it comprehends means for positioning a precious stone, preferably a diamond, above a conical cavity located in a die 5 and means controlled by the operator for lowering the stone into the bottom of the cavity before the metal is poured therein.

An object of the invention is to provide centering devices for the stone before it is lowered into the cavity of the die and pairs of fingers each pair being actuated in unison in a rectilinear path to grasp the girdle of the stone after it descends into the bottom of the cavity thereby holding it in perfect alignment with the axis of the dop.

Another object of the invention is to provide a cam lever connected to each of the fingers which when moved out of action, after the dop is cast, with the stone partly imbedded in its lower end, transmits rectilinear movement to the finger thereby releasing its grip on the stone.

Another object of the invention is to provide means whereby the upper centering member and the lower support for the stone are operated simultaneously to lower the stone and means for moving the upper centering member upwards to swing it out of the way or remove it so as not to obstruct 30 the mouth of the die when pouring the metal.

The novel features of the invention are more fully described in the following specification and claims and illustrated in the accompanying drawing in which:

35 Fig. 1 represents a side elevation partly in section of an apparatus embodying this invention.

Fig. 2 is a horizontal section taken along the line 2—2 of Fig. 1.

40 Fig. 3 is a detail vertical section taken along the line 3—3 of Fig. 2.

Fig. 4 is a vertical section of the dop.

Fig. 5 is a detail view showing the cam lever swung upward.

45 In the drawing the numeral 5 designates a cylindrical column having a chamber 6 provided with an opening 7 located at the rear side of the column. At the upper end of the column is fastened by means of screws 8, 50 a die 9 having a cavity 10 located in its cen-

tral portion. The cavity is conical and it has a vertical face 11 merging into the top while the bottom of the cavity is truncated.

A plunger 12 is slidably mounted to move up or down in a hole situated in the upper 55 wall of the column. The plunger has a yoke member 14 secured to its lower end, the other end of the yoke being connected to a shaft 15 adapted to move up or down in the bore of a bearing 16 extending from the side of the 60 column.

The upper part of the shaft carries a bracket arm 17 which when in use is normally secured to the shaft by means of a set screw 18 threaded in the bearing of the 65 bracket and impinging on the shaft. At the forward end of the bracket is suspended a rod 19 having a lower conical member 20 and an upper ball member 21 coacting with a socket in a member 22 secured to the lower end of 70 the bracket. The bracket is prevented from turning on the shaft when in action by a key 23 but when moved upward along the shaft it can be swung about the shaft.

A plurality of fingers 24 are arranged in 75 radial formation at the upper end of the column and coact with the cavity to grasp a stone 25 when in action. The fingers slide in radial slots formed in the die and they extend outside of the column. Each finger is 80 connected to a lever 26 having a cam or eccentric 27 normally in contact with the side of the column. The cam lever and the finger is pivoted to a support 28 and a spring 29 has a tendency to force the high part or face 85 of the cam against the side of the column. As indicated in the drawing one spring is hooked to two supports 28 so as to give equal pull to both thereby giving each finger the same tension on the stone. 90

When it is desired to cast a dop 30 as shown in Fig. 4 the diamond is positioned between the upper end of the plunger and the conical member 20 situated at the lower end of the universally movable rod as indicated in Fig. 95 1. The shaft 15 is then moved downward thus lowering the plunger and the bracket arm so as to position the stone in the lower part of the cavity as indicated in Fig. 3. The fingers are then operated by swinging 100

two opposite cam levers upward thus moving the cam down as indicated in Fig. 5 and bringing its upper or low face in contact with the side of the column. The contraction of the spring pulls the lever, its support and the finger toward the stone thereby gripping it. Two of the levers are simultaneously actuated to move two oppositely arranged fingers toward the stone in order to prevent displacement of the same. When the stone is securely held by the fingers the bracket arm is moved upward along the shaft out of engagement with the key until the conical member is above the die, then by turning the bracket about the shaft the rod is moved out of the way of the mouth of the die so as not to interfere with pouring the metal into the cavity.

We claim:

- 20 1. In a dop casting machine the combination with a die having a cavity, of a plunger coacting with the die for supporting a stone, means controlled by the operator for simultaneously moving the plunger and centering device to lower the stone into the cavity, means independent of the plunger for moving the centering device upward to clear the cavity, a plurality of fingers made to grasp the stone after it descends into the cavity, 30 and a spring controlled cam lever connected to each finger.
2. In a dop casting machine the combination with a column having a die with a truncated conical cavity, of a plunger movable up 35 and down in the column to cooperate with the cavity, a shaft with a yoke member secured to the lower end of the plunger, a bracket arm movably fixed to the shaft above the die, a universally movable rod depending from the arm above the upper end of the plunger, a plurality of fingers arranged to coact with the lower part of the cavity, and a cam lever relative to each finger for actuating said finger in a rectilinear path outward or 45 away from the axis of the cavity.
3. In a dop casting machine the combination with a column having a die with a truncated conical cavity, of a plunger movable up and down in the column to cooperate with 50 the cavity, a shaft with a yoke member secured to the lower end of the plunger, a bracket arm movably fixed to the shaft above the die, a universally movable rod depending from the arm above the upper end of the plunger, a plurality of fingers arranged to coact with the lower part of the cavity, a cam lever relative to each finger for actuating said finger in a rectilinear path outward or away from the axis of the cavity, 55 60 and a spring coacting with two oppositely arranged cam levers.

In testimony whereof we have hereunto set our hands.

ERNEST LOESSER.

ERNEST W. LOESSER.
